UNITED STATES PATENT OFFICE.

SAMUEL TROOD, OF NEW CASTLE, PENNSYLVANIA, ASSIGNOR TO THE INDUSTRIAL DEVELOPMENT COMPANY, OF NEW CASTLE, PENNSYLVANIA, A CORPORATION OF PENNSYLVANIA.

MACHINE FOR SEPARATING METAL SHEETS.

1,207,668.

Specification of Letters Patent. Patented Dec. 5, 1916.

Application filed July 18, 1914. Serial No. 851,797.

To all whom it may concern:

Be it known that I, SAMUEL TROOD, a citizen of the United States, and a resident of New Castle, in the county of Lawrence and State of Pennsylvania, have invented a new and useful Improvement in Machines for Separating Metal Sheets, of which the following is a specification.

My invention relates to metal plates or sheets, and it has particular reference to means whereby piles or stacks of metal plates, which have become somewhat cemented together or attached to each other in various ways, may be quickly and conveniently separated without damaging the metal.

In order to illustrate the principles involved, the case of steel sheets such as are used in the manufacture of the so-called "tin plate," will be considered, although it will be understood that the method and devices which are applicable here may also be used, with the proper modifications, in many other cases where metal sheets require separation.

In the process of manufacturing steel plate there is a step, after the steel has been rolled down to a certain thickness, in which it is folded double upon itself several times and the entire pack afterward rolled, thereby reducing the thickness of each sheet uniformly until the individual sheets have the required thickness. This is of course done while the pack is hot, and, as a result of the combined heat, pressure and rolling, the sheets become firmly fastened together, partly due to the formation of a slag which acts as a cement, partly due to the very intimate contact between the adjacent plates, and partly to the fact that the small projections and irregularities of the plates are so interlocked that it is necessary to stretch the metal in separating them.

In the present process of manufacture, after the plates have been reduced in thickness as far as desired, they are separated by a slow and expensive hand process, cleaned and pickled and placed in stacks for annealing. After annealing, they are removed from the annealing ovens, cleaned and pickled, after being separated and again rolled, usually cold, thus producing the finished plate, ready for the application of the tin.

From this description it will be evident that present commercial processes usually require the stacks of plates to be opened twice in the course of the manufacture of the sheets and that the hand process now in use is slow, expensive and introduces considerable scrap.

The object of this invention, therefore, is to provide a machine for separating the sheets quickly, cheaply and without damage to them.

In order to separate the sheets it is necessary to accomplish one or more of the following steps: 1st. Break the cementing layer of slag which binds the sheets. 2nd. To overcome the intimate contact between the plates. 3rd. To stretch the interlocked parts sufficiently to eliminate such interlocking.

One notable property of the slag and cement which acts to bind the plates together, is the elastic limit, which, while considerably lower than steel, is still sufficiently high so that a considerable amount of slow bending may take place without causing separation. My experience has shown moreover that the cement and slag, like glass and other silicates, is stronger in compression than in tension, and may be cracked and broken by a quickly applied force, such as a blow, but may not be damaged by a similar force slowly applied.

While the statements here made represent to the best of my belief the theory governing the separation of the sheets, it should be understood that I do not wish to be restricted to the theory set forth.

In application Serial No. 839,188, filed May 18, 1914, the process for which this machine is devised is clearly described.

Referring to the drawings: Figure 1 is a side elevation of one elementary form of my machine. Fig. 2 is a plan view of the machine on a reduced scale. Fig. 3 is a partial front elevation, also on a reduced scale. Fig. 4 shows diagrammatically a detail of the automatic spacing device which determines the separation of the hammers. Fig. 5 shows diagrammatically a detail of one form of spring supported hammer. Fig. 6 shows diagrammatically one form of rotary pneumatic hammer. Fig. 7 illustrates a method of securing the succession of rapid blows by means of an electric vibrator. Fig. 8 shows schematically an alternative arrange-

ment of rolls and levers to accomplish substantially the same results as the construction shown in Fig. 4.

In the following description of the drawings it should be kept in mind that only the essential elements of my machine are here shown in a diagrammatic manner and it is the general assemblage of certain fundamental elements which is here disclosed, rather than the details of the manner of construction of the elements.

Referring to the figures: (1) represents the frame of the machine, on which bearing blocks (2)—(2^A) slide in guideways, (3)—(3^A); bearing blocks, (2)—(2^A) carry the hammer elements, (4)—(4^A) which as here constructed are composed of end plates, (5) which support rods, (6) on which are loosely mounted the rings, (7) which deliver the blows on the rotation of the device. The hammer elements (4), are mounted on shafts (8), and arranged to be driven by chains or belt, numbers (9) (9^A) from any source of power, such as shaft (10). A spring tension-pulley (9^B) maintains the necessary tension on the belt for driving the hammers.

One bearing block, as, for example (2), is arranged to be pushed downwardly by spring (11), which is adjusted by screw (12), and locked at the desired tension by nuts (13) and (14).

Two sets of rolls (15)—(15^A) are provided, to serve the double purpose of driving the sheets (17) through the machine and also automatically adjusting the hammer elements (4) to the proper separation. The rolls (15)—(15^A) are mounted on shafts (16)—(16^A), the gears (18), being provided to drive the two rolls of a set at the same speed. Chain members (19) and (20) transmit the necessary driving force from any convenient source, such as shaft (10).

One preferred form of hammer member which is shown on the drawing, consists of a series of steel rings loosely mounted on steel rods disposed around the circumference of a cylinder. The rings are forced outward by centrifugal force when the hammer is rotated. They remain in this position until they encounter some object such as a pack of sheets, which they strike a glancing yielding blow.

Fig. 4 will best illustrate the manner in which the rolls adjust the separation of the hammer elements (4)—(4^A). Lever (21) is pivoted to the frame (1) by pivot (22), and supported at its upper end by bearing blocks (23). Lever (24) is pivoted to the frame (1) by pivot (25), and at its upper end supports bearing block (2) which carries the upper hammer element (4). A pin (26) positioned between levers (21) and (24) serves as a fulcrum such that an upward movement of roll (15) produces a corresponding upward movement of hammer ele-

ment (4), the relative amounts of these movements being determined by the lengths of the levers. It will be evident, therefore, that when the levers are properly adjusted the entrance of the pack of sheets between rolls (15) (15^A) will automatically regulate the separation of the hammer elements for most effective treatment. The blows of the hammer elements will, therefore, be always automatically adjusted for most effective operation.

In Fig. 5, reference numeral (30) represents a section of the beating rolls of the hammer elements, while (31) represents the hammers which are inserted in the roll (30) and drawn inward by the spring (32) acting on plate (33) which is fastened to stem (34) carried by hammer (31). The shaft on which the roll is mounted is shown in section by (35).

Fig. 6 shows a construction somewhat similar to that of Fig. 5, except that the springs (32) are replaced by air chambers (36) in the roll (37) and closed at their outer end by plunger (38) which carries hammer (39). One end of plunger (38) carries piston (40) which acts to compress the air as the roll is rotated, thus working against centrifugal force to produce a resilient blow. A readily compressible liquid or solid may fill space (36) instead of a gas if desired. The shaft (40^A) on which roll (37) rotates is shown in section.

In Fig. 7, the hammer elements (41) are carried on support (42) by yoke (43), the upper portion of which is magnetic. Shaft (44) fastened to yoke (43) may also be magnetic, and passes through coil (45) which acts as a magnet. The guard (46) fastened to shaft (44) is acted upon by spring (47) which serves to counteract the weight of moving parts, thereby assisting in the production of a rapid blow. A shell (48) is shown around coil (45) and is preferably made from magnetic material. A portion of the table (49) on which the plates are laid is shown with a pack of plates (50) in position for being treated. One terminal of the coil (45) is arranged to be connected to a suitable source of potential, while the other terminal is connected to a vibrating contact (51), the complementary terminal (52) being shown mounted upon an extension of the yoke (43). The contact is so arranged that on supplying current the coil will be energized, thus causing the yoke to be lifted. The lifting of the yoke however opens the circuit, thus causing the yoke and hammer members carried thereby to drop, thus delivering the blow. The downward motion of the yoke closes the circuit and the cycle is thus repeated very rapidly.

Fig. 8 shows a mechanism arranged to separate the beating rolls in proportion to the thickness of the pack of plates to be

separated. (53) and (54) represent the beating rolls of a machine similar to that illustrated in Fig. 1, the beater (54) being mounted on a stationary bearing, while beater (53) is carried in bearing (55) which is supported by lever (56) pivoted at fixed pivot (57). The lever (56) is supported by link (58) at pivot (59). The lower end of link (58) rests upon guide roll (60) which is 10 lifted or lowered automatically by passing over the pack (61) of sheets to be separated. (62) represents a stationary pivoted guide roll co-operating with guide roll (60).

In Fig. 1, a rack (27) and pinion (28) 15 are shown, thus providing means of adjusting the ratio of the lever elements, as desired. An adjusting screw (29) is also provided to make proper compensation for variation in dimensions, differences between 20 solid pack and loosened pack, etc.

From the above description it will be evident that when the machine is in operation, with the rolls and hammer elements rotating, the sequence of events will be as following: On feeding the pack (17) between 25 rolls (15) (15^a), these rolls grip the pack and force it through the machine guided by the channels (30—30^a). The entrance of 30 the pack between the rolls also automatically spaces the hammer elements so that when the pack reaches them it will be subjected to a series of very rapid blows of the desired force, the blows being delivered both on the top and bottom of the pack. As the pack 35 passes through the machine each portion of the surface is in turn subjected to the blows, thereby separating the plates over their entire surface. It will be noted that the construction of the hammer element 40 results in providing blows of extreme resiliency, since the centrifugal force of the loose rings determines the force of the blow, and the looseness of the rings eliminates all 45 tendency for tearing, scratching or otherwise deforming the sheet. On consideration it will be evident that the rotation of hammers (4), which are equipped with a considerable number of loose rings, when rotated at a speed of 3,000 revolutions per 50 minute will give 2,880,000 blows per minute to any portion of the plate, and each blow will have a force of many pounds. The result of the rapid succession of blows is 55 to readily separate plates which are held together most tenaciously. An additional result is to polish thoroughly the side of the plate exposed to the hammering action. This polish may be sufficient to give a finish which is the equivalent of a cold rolling 60 process and may therefore materially improve the quality of the finished plate. It appears also, from tests which have been made, that the treatment by numerous rapid blows may act to render the texture of the 65 iron finer.

Obviously various groupings of the elements here described may be used, and the same results secured. Thus a very rapid pneumatic hammer, an electric hammer or vibrator and other means may be used to 70 secure the series of rapid impacts, while various mechanical equivalents may be employed in place of the lever device shown for spacing the hammers.

In this specification and in the claims 75 the term "resilient hammer" refers to the member indicated by reference number 4, or the equivalent of that member, which may obviously be secured by employing springs, 80 air cushions, or well known equivalents.

The term "guides" is intended to designate the guide rolls or similar devices which direct the sheets through the machine.

The mechanism assembly, shown diagrammatically in Fig. 4, represents one form of 85 automatic adjusting member, although there will obviously be many other constructions adapted for accomplishing this result, without departing from the spirit of this invention.

The term "driving members" designates the means which are employed to drive the pack through the machine.

In the device here illustrated the guides 90 or guide rolls act as driving members, forcing the pack through the machine. This may be accomplished by separate driving rollers, however, if desired, this function being substantially the same in either case.

Having now fully described my invention, what I claim as new and desire to secure by Letters Patent is as follows:

1. A machine for separating metal sheets, comprising a frame, resilient hammer members supported thereon, guides, and connecting members for transmitting the motion of the guides to the hammer members.

2. A machine for separating metal sheets containing a frame, a resilient hammer member supported thereby, and an automatic device for adjusting the position of the hammer member.

3. A machine for separating metal sheets, comprising a resilient hammer member, a support for said resilient hammer member, and an automatic spacing device arranged to regulate the force of the blow of the said hammer member.

4. A machine for separating metal sheets, comprising a frame, supporting a resilient 120 hammer member, driving members for moving the sheets in contact with the hammer member and guides for automatically adjusting the position of the hammer member.

5. A machine for separating metal sheets, comprising a resilient hammer member, a frame, a support for the sheets to be separated, and an adjustment for controlling the distance between said support and said 125 hammer member.

6. A machine for metal sheets, comprising a frame, a resilient hammer member supported thereon, directing means for controlling the path of said sheets through the machine, and roller members for controlling the speed of the sheets through the machine.
7. A machine for separating metal sheets, comprising a frame, a resilient hammer member supported thereby, guides for said metal sheets, and an adjusting device for controlling the distance between said hammer member and said sheets.
8. In a machine for separating metal plates; a plurality of rotating hammers arranged to act on the plates from two surfaces simultaneously, said hammers consisting of loosely mounted members arranged around the periphery of a cylinder.

In testimony whereof, I have hereunto 20
subscribed my name this thirteenth day of
July, 1914.

SAMUEL TROOD.
